UNITED STATES PATENT OFFICE.

CHARLES T. SCHOEN, OF PHILADELPHIA, PENNSYLVANIA.

CORNER-BAND FOR CARS.

SPECIFICATION forming part of Letters Patent No. 437,723, dated October 7, 1890.

Application filed July 30, 1890. Serial No. 360,393. (No model.)

To all whom it may concern:

Be it known that I, CHARLES T. SCHOEN, a citizen of the United States, residing at Philadelphia, in the county of Philadelphia and 5 State of Pennsylvania, have invented a certain new and useful Improvement in Corner-Bands for Railway-Cars, of which the following is a full, clear, and exact description.

This invention relates to pressed-steel corner bands or straps for railway-cars.

The object of the invention is to improve the construction and appearance of such bands or straps.

The invention consists in pressed-steel corner-bands made in pairs, re-enforced longitudinally at their bend or angle, and adapted to be applied in pairs on the outside and inside of the corners of cars, substantially as I will proceed now more particularly to set forth 20 and finally claim.

In the accompanying drawings, illustrating my invention, in the two figures of which like parts are similarly designated, Figure 1 shows in perspective the outer and the inner bands, 25 and Fig. 2 shows the same in longitudinal central section.

The outer band *a* is made usually as a right angle with the longitudinal central ribs *b* of the two sides, which merge into the circular, 30 oval, or other shaped rib *c* at the angle or corner. The ribs *b* and *c* project outwardly from the face of the band. The inner band *d* is also made as a right angle and has the side ribs *e* merging in a corner or angle rib 35 *f* of oval or other shape. The ribs *e* and *f* are sunk into the plate, viewing the plate as shown in Fig. 1 and as clearly indicated in Fig. 2.

The essential feature of the ribs *c* and *f* is 40 that while they are a continuation of the side ribs, respectively, of the outer and inner plates they diverge from the said side ribs so as to cover practically the top and bottom of the

corner, and thus make the corner very strong. By forming the side ribs in the center of the 45 band room is left on each side of such ribs for the insertion of rivets or fastening-bolts in the holes *g* and *h*. By sinking the ribs in the inner plate there is left a flat surface of said plate to come into contact with the boards 50 or other material used in the construction of the sides and ends of the car. Of course these ribs very materially stiffen and strengthen the bands, and, in addition, they impart a bold and good finish to the corner of the car. 55

Corner-bands constructed in accordance with this invention are applied to cars in pairs in the ordinary manner. These corner-bands may be made to interchange with the corner-bands in common use. They are struck up 60 from plate-steel, by preference, in usual manner, and the holes made by drilling, punching, or otherwise, as may be desirable or convenient.

What I claim is— 65

1. Pressed-steel corner-bands for cars, constructed with central longitudinal side ribs and an angle or corner rib diverging from yet connecting the side ribs, substantially as described.

2. Pressed-steel corner-bands for cars, made in pairs, the outer band having outwardly-projecting side ribs and an angle or corner rib diverging from yet connecting with the side ribs, and a complementary inner band having 75 sunken side ribs and an angle or corner rib diverging from yet connecting with the side ribs, substantially as and for the purpose described.

In testimony whereof I have hereunto set 80 my hand this 29th day of July, A. D. 1890.

CHARLES T. SCHOEN.
